UNITED STATES PATENT OFFICE

EDWARD J. ABBE, OF CLEVELAND, OHIO, ASSIGNOR TO THE ELWELL-PARKER ELECTRIC COMPANY, OF CLEVELAND, OHIO, A CORPORATION OF OHIO

INDUSTRIAL TRUCK

Application filed February 5, 1927. Serial No. 186,087.

This invention relates to industrial trucks, particularly to the type known as a tier lift truck, which embodies an upright frame and a carriage suitable for receiving a load and mounted to traverse the frame to receive or discharge the load at various heights. The primary object of the invention is to provide a truck of this character, but in which the upright frame is tiltable, with power throw out mechanism which shall operate when the carriage has reached a definite position relative to the frame without regard to whether or not the frame is tilted at this time.

A further object is to provide a simple power throw out mechanism which will operate when the upright frame has been tilted to a predetermined position as well as when the carriage is moved to a predetermined position.

Further objects and features of the invention will become apparent from the following description relating to the accompanying drawings. The essential characteristics are summarized in the claims.

In the drawings, Fig. 1 is a side elevation of an industrial truck with my invention incorporated therewith; Fig. 2 is a fragmentary side elevation similar to Fig. 1 of the boom in tilted position, the main portion of the truck frame being broken away; Fig. 3 is a partly diagrammatic view showing the selective operation of the hoisting motor on either of two hoisting drums; Fig. 4 is an electrical diagram showing a convenient switch adaptable to my invention for controlling the motor.

In the use of industrial trucks of the tier lift type it is highly desirable to limit the movement of the load carrier or tier lift carriage by a power throw out mechanism for stopping, or rendering ineffective, the motor which operates to raise the carriage. To provide such a throw out device is comparatively simple when the track way for the carriage is rigid on the truck frame. However, when the carriage track-way is arranged to be tilted trouble arises in locating the controlling trip or trigger for operating the power throw out mechanism at any definite position and maintaining it in such position re-

gardless of the tilting movement of the track-way. One of the purposes of my invention is to overcome this difficulty in a simple and expeditious manner. I accomplish this by arranging a system of linked movable control members two of which are pivotally attached to each other coaxially with the pivot of the trackway, whereby the tilting of the trackway will not change the relation of such control members.

Referring in detail to the drawings, 1 indicates the frame of an industrial truck of a known type having rear traction wheels 2 suitably driven by a motor (not shown), and a pair of dirigible front wheels 3 suitably controlled from the rear of the truck by linkage (not shown). A similar truck may be found in the prior patent to Clyde E. Cochran No. 1,538,168 issued May 19, 1925. The power for such a truck may comprise electric batteries located in a battery housing 5 surrounding the rear wheels. An operator's platform is indicated at 7 on which the operator may stand within reach of the various control levers shown at the left hand of Fig. 1.

Intermediately of the two sets of wheels is shown a hoisting unit 10 comprising a motor 11 and a pair of hoisting drums 12 and 13, one of which may be arranged to tilt an upright frame or trackway and the other to raise or lower a carriage guided by the frame.

The upright frame as shown comprises a suitably braced rigid frame or boom member 15 having rearwardly extending arms, one being shown at 16 pivoted as at 17 to upstanding brackets 18 on the forward end of the truck frame 1. The carriage or tier lift 20 may be mounted on suitable rollers, such as 21 and 22 which ride along guiding members, such as for example as the flanges of structural channels or angles comprising the skeleton of the upright frame. The carriage has a forwardly extending L shaped platform 23 to engage beneath a load.

The means herein shown for raising and lowering the tier lift carriage includes the hoisting mechanism, above mentioned, particularly the drum 13 about which is wound a cable, such as 25 passing forwardly over a

sheave 26, thence upwardly to a sheave 27, surmounting the upright frame, and then downwardly as at 25 to the carriage 20. The means for tilting the frame may comprise a cable 30 attached to the drum 12 and passing upwardly over a sheave 31 attached to the upper end of the frame, the outer end of the cable being secured as at 32 to a hook rigid on the main truck frame.

Convenient means for selectively controlling the drums 13 and 15 from a single motor is shown in my prior Patent No. 1,688,131, issued October 16, 1928. Fig. 3 of the present drawings shows the essential elements of such a control, the drive shaft of the motor 11 being connected by a beveled gearing 33 to a slidable clutch sleeve 34 drivingly rigid with one of the beveled gears. A shaft 35 is driven when the clutch 34 is in one position, the drum 12 being driven through a worm 37 on the shaft meshing with a worm gear 38 on the drum. The other drum, namely 13, is similarly driven through shaft 40, worm 41 and worm gear 42. The clutch sleeve 34 may be moved from one position to another through suitable linkage including a bell crank 43 and link 44 near the rear end of the truck. The handle 45 at the very top of the rear portion of the truck frame may have suitable connections (not shown) with the bell crank 43.

A convenient location for a switch for energizing the motor 11 is near the rear of the truck, whereby if desired the switch may be easily controlled by both hand and pedal operated levers. Such a switch is shown at 50 and may comprise the arrangement of contacts and brushes shown in Fig. 4, hereinafter more fully described. The switch, as shown, has a connection through a link 51 to an arm 52 pivoted at the rear of the frame and for the present it may be assumed that this is the only operator's control for the switch. The switch may comprise a drum, carrying contacts such as 50^a, 50^{a'}, 50^b, 50^c and 50^d. Current may be fed to the contacts 50^a and 50^b from a power unit, such as a battery B through conductors 55 and 56. The motor as shown has an armature A fed by current from the battery in a constant direction regardless of the "on" position of the switch, while the current through the field F may be reversed by manipulation of the switch to reverse the direction of rotation of the motor. The field is connected by conductors 57 and 59 to stationary switch contacts 58 and 60, adapted to wipe across adjacent pairs of movable contacts 50^{a'}—50^a and 50^c—50^d respectively. The contacts 50^a and 50^c are shown as electrically connected, likewise the contacts 50^b and 50^d. Contacts 50^a and 50^{a'} are virtually one contact, broken to provide for cutting off power to the armature in the position of the switch shown, and arranged to feed current delivered from the

battery through conductor 55 to the armature through the conductor 55' from which it returns to the battery through the conductor 56'. With this arrangement when the drum is rotated to the left current will flow through the field in one direction, and it may be assumed that this will drive the motor to raise the carriage or tilt the upright frame, depending on which one of the worm and gear mechanisms is rendered active through the clutch sleeve 34. If the drum is rotated in the opposite directions namely, clockwise, current will flow through the field in the opposite direction for either returning the frame to upright position or for lowering the tier lift carriage. When the drum is in the position in Fig. 4, the motor will be idle.

The kick-off or power throw out arrangement comprises a forwardly extending link 62 pivotally connected at one end, as at 61, with the switch drum and supported at its other end by a depending lever 63. Slidably pivoted to this lever 63 is another link 64 extending forwardly to a short depending arm 65 to which arm the front end of the link 64 is pivoted at 66 coaxially with the pivot of the upright frame 15. In order that the upright frame when rotated about its pivot to the left may operate the links 62 and 64 to throw off the power I provide a collar 67 rigid on the link 64, a sleeve 68 slidable on the link 64, and a link 69 pivotally attached as at 69^a to the member 16 of the frame 15 and connected with the sleeve. As the frame 15 is tilted as above mentioned the sleeve slides along the link 64 until it engages the collar 67 whereupon an abutment 64^a on the link 64 engages the arm 63 and thrusts the link 62 rearwardly, returning the switch to the off position as shown in Fig. 4.

To enable the carriage to throw off the power through the same linkage, 62 and 64, I provide a bell crank 70, pivoted as at 71 to the side of the frame 15 and connected by a link 72 to the short depending arm 65, and a link 73 extending upwardly from the bell crank to a bail 75 pivoted as at 76 to the sides of the frame 15. The bail normally rests on pins 78 (one being shown) rigid with the frame. The transversely extending portion 75^a of the bail is positioned in the path of the roller 21 and when the carriage 20, carrying this roller, is hoisted to its highest allowable position it will rotate the bail about its pivot and, through the linkage described, throw the switch to off position.

As will be seen from Fig. 2 the frame 15 may tilt without moving the control links 62 and 64 until the sleeve 68 contacts with the collar 67. It follows that the frame 15 may be tilted considerably and the carriage then hoisted, but the point in the travel of the carriage at which the power is thrown off will be the same as if the frame were upright.

Once the power has been thrown off either by the tilting of the frame 15 or the raising of the carriage the operator must manually operate the switch to reverse the motor and allow the control links 62 and 64 to assume their original position before the carriage can be again raised or the frame again tilted. In other words, the power kick-off acts as a mechanical lock on the switch preventing the operator from manipulating the switch to cause further upward movement of the carriage or further tilting of the upright frame.

I claim:

1. In combination, an upright tilttable frame, a carriage movable along the frame, power operated hoisting mechanism for so moving the carriage, and automatically operating power throw out mechanism for cutting

off the power to the hoisting mechanism when the carriage has moved to a definite position relative to the frame irrespective of whether the frame is in upright or tilted position.

2. In an industrial truck having a body and a tilttable trackway affording frame at one end thereof, load engaging means mounted on and guided by the trackway, means for tilting the frame, power means for moving the load engaging means along the frame, and power throw-out means associated with the frame and movable therewith, said throw-out means being arranged to be actuated when the said load engaging means reaches a definite position on the trackway, irrespective of the tilted position thereof.

3. In combination with an industrial truck having a tilttable trackway, a load engaging member guided by the trackway, power means for moving the member along the trackway, and power throw out means operable automatically consequent upon the member being moved to a definite position relative to the trackway, irrespective of the tilted position of the trackway.

4. In combination with a truck, a main frame, a tilttable boom mounted in upright position on the frame, a raisable platform arranged to traverse the boom, a power hoist connected with the platform to raise it, manually operated mechanism in fixed position on the truck and remote from the boom for throwing the power into operation, and a device carried on the boom and acting on said mechanism to throw off the power when the platform is raised to a predetermined position relative to the boom irrespective of the tilted position of the boom.

5. In an industrial truck, a frame, a tilttable trackway pivoted on the frame, a load engaging member mounted to traverse the trackway, a motor, means to connect the motor selectively to the trackway to tilt it and to the said member to move it along the trackway, and mechanism for stopping the

motor arranged to be actuated by the tilting movement of the trackway and by the movement of the said member to a predetermined position on the trackway.

6. In combination with a truck, a truck frame and power operated hoisting mechanism supported thereby, a swingable upright trackway, connections from the hoisting mechanism and arranged to tilt the trackway, a platform movable up and down on the trackway and connections from the hoisting mechanism for so moving the platform, means for selectively controlling said hoisting mechanism to either tilt the trackway or raise the platform, and means actuated by a given tilting movement of the trackway or a given raising movement of the platform and operating to cut off the power supply to said hoisting mechanism.

7. In a truck, a truck frame and hoisting mechanism supported thereby, electric power means for operating the hoisting mechanism, a tilttable frame connected with the hoisting mechanism, a platform movable up and down the tilttable frame and connected with the hoisting mechanism, a manually operable switch for controlling the power, and power throw out means connected to said switch and actuated by a given tilting movement of the tilttable frame, and also consequent upon the platform reaching a definite position on the tilttable frame.

8. In combination a vehicle frame, an upright member pivoted to the frame, means for swinging the member on its pivot, a load engaging member mounted to traverse the upright member, power means to cause such traversing movement, means carried by the frame to render said power ineffective, a lever pivoted to said upright member, a link operatively connected to said last named means at one end and pivotally connected to an arm of said lever coaxially with the pivot of the upright member at the other end, and means operatively connected with the lever and disposed to be engaged by said load engaging member, whereby the load engaging member will at all times operate the power controlling means at a definite position with respect to the upright member.

9. In a vehicle, an upright pivoted trackway, a load engaging member mounted to traverse the trackway, a power hoist having connections with the trackway to tilt it and connections with the said member to cause such traversing movement, mechanism to interrupt the supply of power to the hoist, a link operatively connected to the mechanism, means actuated by the load engaging member when moved to a predetermined position, said means being positively connected to said link, and a member attached to the trackway, said member being slidably supported by the link and arranged to engage an abutment on said link, whereby tilting of the

trackway to a predetermined position actuates the power interrupting mechanism.

10. In a truck, a frame, a tiltable trackway pivoted at one end thereof, electrically operated hoisting mechanism rigidly mounted on the truck frame, connections therefrom to tilt the trackway, a carriage mounted to traverse the trackway, connections between the hoisting mechanism and carriage to effect such traversing movement, a control switch manually operable to energize the motor of the hoisting mechanism, a rod connected with the switch at one end and pivoted coaxially with the boom at the other end, carriage engaging means on the trackway and connections between said means and the pivoted end of the control rod for throwing the switch to off position when the carriage reaches a predetermined position on the trackway.

11. In combination with a truck, a frame, a power operated hoisting unit mounted thereon carrying two drums, a tiltable trackway mounted on said frame, means connecting the trackway to one of said drums for tilting the trackway, a carriage mounted to traverse the trackway, and means connecting the carriage with the other of said hoisting drums to raise the carriage, manual means for throwing on the power to drive said drums and means controlled either by a given tilting movement of the trackway, or a given raising movement of the platform for throwing out said power.

35. In testimony whereof, I hereunto affix my signature.

EDWARD J. ABBE.
